DESIGN FOR A HOLDER FOR FISHING POLES OR THE LIKE

George F. Hilts, Grand Rapids, Mich.

Application June 7, 1940, Serial No. 92,874

Term of patent 3½ years

To all whom it may concern:

Be it known that I, George F. Hilts, a citizen of the United States, residing at Grand Rapids, in the county of Kent and State of Michigan, have invented a new, original, and ornamental Design for a Holder for Fishing Poles or the like, of which the following is a specification, reference being had to the accompanying drawing, forming part thereof.

for fishing poles or the like, showing my new design.

I claim:

The ornamental design for a holder for fishing poles or the like, as shown.

GEORGE F. HILTS.
